BOILER

William Robitzek, City Island, and Leonard J. Bachler, New York, N. Y.

Application March 8, 1939, Serial No. 260,474

2 Claims. (Cl. 122—75)

This invention relates to boilers, especially of the down and cross draft type.

It is the principal object to provide such a boiler made of a unitary structure which can be manufactured economically.

Another object is to provide a boiler of this kind in which there are no caulked joints necessary and in which all joints are welded to form a single main structure.

10 A further object is to eliminate any moving parts such as blowers, fans and the like and so dispose the combustion space with respect to the air inlets that very fine fuel such as buckwheat coal may be used.

15 A still further object is, by the disposition of the water tubes and water legs of the boiler in relation to the fire box or combustion chamber, to obtain a maximum heating efficiency and utilize to the fullest extent all available heating units.

20 Still another object is to combine the usual separate ash pit with the main boiler in one unit and to make provision for the use of flooring for the ash pit in installation where no foundation has been arranged for.

25 Other objects will become apparent in the following specification and the accompanying drawings in which

Fig. 1 is a vertical cross sectional view through 30 a boiler embodying the principles of the invention;

Fig. 2 is a longitudinal section along the plane of line 2—2 in Fig. 1; and

35 Fig. 3 is a sectional view similar to Fig. 1 but having duplicate coal charging and storing facilities.

The same characters of reference denote similar parts throughout the several views.

The drawings are shown more or less diagrammatically and those accessories appertaining to boilers and well known in the art have been omitted in part.

In Figs. 1 and 2, 10 is a shell substantially oval shaped in cross section defining a water chamber 11 having a front wall 12, a rear wall 13, a top wall 14 and a bottom wall 15. Extending longitudinally along the bottom wall 15 of the shell 10, projecting downwardly therefrom and in spaced relation to its side wall is another wall 16 forming a water leg 17. 18 are a series of oblique water tubes, oval in cross section and close to each other, connecting the lower part of the water leg 17 with the lower part of the water chamber 11.

55 At the side of the shell 10 opposite to the water

leg 17 is an outer chamber or magazine 19 defined by a wall 20 having a cover 21, and an obliquely downwardly extending side wall 22. 23 is an air inlet controlled by a suitable damper 24, and 25 is a continuation of the outer wall 20 to the floor line. Similarly the outer wall of the shell 10 alongside the water leg 17 is continued downwardly to the floor line.

26 are bottom grates, slightly inclined in spaced relation to the floor line and forming an ash pit 10 therewith and extending from the bottom of the water leg 17 to the outer wall 25. The bottom grates are connected by suitable means and adapted to be operated for shaking purposes in the usual and well known manner. 28 is an ash pit door. 29 is a series of inclined vertical grates connected at their tops 30 to the wall 22 adjacent the air opening 23 and terminating immediately above the bottom grates in spaced relation to the outer wall 25 forming an air chamber 31 therewith. 32 are spacing bars attached to the grates to fix their position with respect to the wall 25.

The space between water tubes 16, bottom grates 26, water leg 17 and the bottom 15 of the chamber 11 defines a combustion chamber 33. 34 is a supplementary combustion chamber at the rear of the chamber 33 disposed between rear wall 13 of shell 10 and a recess formed by walls 35 and 36.

30 The front wall 12 of the shell 10 is provided with a clean-out chamber 37 having a clean-out door 38 of the usual design. The rear wall 13 is provided with a smoke box 39 having the usual stack connection 40 and damper 41.

35 42 are a series of short fire tubes connecting the supplementary combustion chamber 34 with the clean-out chamber 37, and 43 are a series of long fire tubes connecting the clean-out chamber 37 with the smoke box 39.

40 44 is a cast iron bottom plate fastened, respectively laid upon flanges 45 of the walls 12, 13, 16 and 25 forming the ash pit 27.

The entire structure with exception of the grates, floor plate, doors, dampers and other customary accessories, some of which are not shown, is made of a single sheet of metal welded together, thus avoiding all caulked or screwed joints.

45 The operation of the boiler is as follows:

After an initial fire has been built upon the bottom grates 26 in the combustion chamber 33, the magazine 19 is charged with coal which ignited fills the combustion chamber 33 surrounding the small water tubes 18 and contacts 55

with the lower part of the water leg 17. Air is drawn in through the inlet 23 and the vertical grates 29, as well as through the bottom grates 26 by the draft from the stack.

5 The gases of combustion are drawn first through the short fire tubes 42 into the clean-out chamber 37 and thence through the long fire tubes 43 into the smoke box and the stack.

Because only a single thickness of metal is 10 interposed between the combustion chamber and the water in the water leg and tubes as well as the bottom of the water chamber, the water contained therein is quickly heated. The products of combustion or gases, also being separated from 15 the water while travelling through the fire tubes by only a single thickness of metal, give up their maximum heat values to the water whereby a relatively high boiler efficiency is obtained.

In the modification illustrated in Fig. 3, the 20 coal magazine is duplicated, that is, a magazine is provided for at both sides of the main shell. The same characters of reference are used as in Figs. 1 and 2. The details of construction and description of operation are identical therewith. 25 The double magazine is especially provided for on boilers for larger buildings and where therefore greater coal reservoirs are of advantage.

The floor plate at the bottom of the ash pit is optional and may be used particularly where no 30 foundation has been prepared for the boiler and where preferably a completely self-contained unit is to be installed.

A boiler made according to the principles of this invention may be assembled, exclusive of 35 its accessories, and moved directly to the job because of its appreciably lesser weight than boilers as made heretofore in sections and of heavier metal.

While we have shown in the drawings several 40 preferred embodiments of the invention, it is understood that various changes in the form, proportion and minor details of construction may be resorted to without departing from the principles or sacrificing any of the advantages of the 45 invention, as defined in the appended claims.

What we claim as new is:

1. A boiler of the down and cross draft type 50 consisting of a casing having a water chamber at its top, a water leg at one side thereof downwardly extending therefrom, a series of inclined water tubes connecting the lower part of the said water leg to the bottom of the said water chamber at the other side thereof, a fuel reservoir alongside said other side of the chamber having a charging inlet at its top and an air inlet at its 55

side, the outer walls of the said casing extending to the floor, short fire tubes and long return fire tubes through the said water chamber and in communication with each other and a combustion chamber within the casing below the said water chamber, the said casing having a stack outlet in communication with the said return fire tubes, all formed in a unitary structure of sheet metal having welded joints, a series of bottom grates in spaced relation to the floor extending laterally between the bottom of the water leg and the opposite outer wall of the casing, and a series of vertical grates in spaced relation to the said last mentioned outer wall and defining an air chamber therewith extending from adjacent the 10 said air inlet to the said bottom grates, the outer walls of the said fuel reservoir and the said air chamber being a continuous sheet of metal and part of the said outer walls of the casing. 15

2. A boiler of the down and cross draft type 20 consisting of a casing having a water chamber at its top, a water leg at one side thereof downwardly extending therefrom, a series of inclined water tubes connecting the lower part of the said water leg to the bottom of the said water chamber at the other side thereof, a fuel reservoir alongside said other side of the chamber having a charging inlet at its top and an air inlet at its side, the outer walls of the said casing extending to and being inwardly flanged at the 25 floor, short fire tubes and long return fire tubes through the said water chamber and in communication with each other and a combustion chamber defined by the said outer walls of the casing below the said water chamber, the said casing having a stack outlet in communication with the said return fire tubes, all formed in a unitary structure of sheet metal having welded joints, a series of bottom grates in spaced relation to the floor extending laterally between the 30 bottom of the water leg and the opposite outer wall of the casing forming an ash pit with the floor, a series of vertical grates in spaced relation to the said last mentioned outer wall and defining an air chamber therewith extending from 35 adjacent the said air inlet to the said bottom grates, the outer walls of the said fuel reservoir and the said air chamber being a continuous sheet of metal and part of the said outer walls of the casing, and a removable floor plate adapted 40 to rest upon the said inwardly flanged outer walls of the casing. 45
